UNITED STATES PATENT OFFICE.

WILLIAM J. STANTON, OF BAYONNE, NEW JERSEY.

CORKSCREW.

No. 884,873.

Specification of Letters Patent.

Patented April 14, 1908.

Application filed March 12, 1907. Serial No. 362,013.

To all whom it may concern:

Be it known that I, WILLIAM J. STANTON, a citizen of the United States of America, residing at Bayonne, in the county of Hudson, 5 and State of New Jersey, have invented new and useful Improvements in Corkscrews, of which the following is a specification.

This invention relates to improvements in cork-screws, its object being to provide a device of this character by which corks may be conveniently extracted from bottles without the necessity of using great force in extracting the most refractory corks and without liability of breaking the bottles.

15 In the accompanying drawings,—Figure 1 is a vertical longitudinal section through the cork-screw and the neck of a corked bottle, showing the screw in position for use. Fig. 2 is a similar view, showing the cork-screw inserted and the parts in position for extraction.

Referring to the drawing, 1 designates a tubular frame or casing provided with an outwardly flared or bell-mouthed lower end 2 adapted to receive and inclose the upper end of the neck of the bottle from which the cork is to be extracted, the reduced portion of the upper end of the bell-mouthed part being adapted to bear against the rim edge of the 30 bottle neck, as shown in Fig. 2. The upper end of the tubular frame or casing is formed with a threaded opening 3 of reduced diameter with respect to the bore or passage 4 of said casing, the crown of the casing thereby being adapted to serve the function of a relatively stationary nut for use in conjunction with the operating screw of the extracting means.

A screw threaded spindle 5 extends into 40 the passage 4 and works in and through the screw threaded opening 3 and is provided at its upper end with a grip or operating handle 5^a. At the lower end of the threaded portion of this stem a clutch member 6 is provided upon the stem, said member comprising a disk or head fixed to the stem and having clutch teeth, each formed with a straight shoulder and a reverse beveled surface. Below the clutch member 6 the stem 45 extends in the form of a reduced extension 7 which is cylindrical in form and smooth-surfaced and is journaled to rotate in a bearing 8 formed in a head 9 to which is fixed the cork-screw 10. The upper end of the head 9 is 50 provided with clutch teeth, forming a clutch member 10' to coöperate with the clutch

member 6, the teeth upon said member 10 being reversely arranged with respect to the teeth upon the member 6. The construction of the two clutch members is such that when the member 6 is brought down into engagement with the member 10' and is turned to the right the clutch teeth will interlock and turn the head 9, while a reverse movement of the member 6 will cause the teeth thereof to ride upward on and slip over the teeth of the clutch member 10, whereby retrograde rotation of the screw 5 will withdraw the member 6 from engagement with the member 10'.

Instead of the clutch construction described, I may employ any other suitable clutch, adapted to operate in like manner. The lower end of the spindle extension 7 projects into a vertical transverse slot 11, formed in the lower end of the head 9 and terminates in a reduced polygonal portion 12 on which is fitted a collar or contact head 13. This collar or contact head is provided with a receiving socket for the portion 12 corresponding in form thereto so that said collar when fitted in position will be held from rotation, but said portion 12 and collar may be of any other form or construction to effect such a character of connection and any suitable equivalent for the collar may be used. A pin or other suitable fastening device 14 passes transversely through the collar and portion 12 and secures the collar against downward movement and disconnection under the strain of extracting a cork.

In the drawing, I have shown in Fig. 1 the device in position for application to withdraw a cork 15 from the neck 16 of a bottle or similar container, from which it will be understood that the casing 1 is held in one of the hands of the operator above the bottle to bring the lower end of the screw 10 into position for insertion into the cork. The device is set for operation by the action of the operator turning the handle 5^a by the use of his other hand in a clock-wise direction until the spindle 5 has traveled down far enough to bring the clutch member 6 into engagement with the clutch member 10', thus coupling the cork-screw to the threaded spindle. As a result a continued rotation of the spindle to the right will cause the cork-screw to turn therewith, by which it will be screwed into the cork until fully inserted, as shown in Fig. 2, this operation drawing the casing 1 down until the bell-mouthed portion 2 thereof rests upon the upper end of the neck. When

the cork-screw is thus fully inserted the spindle 5 is turned to the left, thereby moving the clutch member 6 out of engagement with the clutch member 10' and freeing the spindle 5 from the head 9, a continued upward movement of the spindle serving to draw the collar upward against the upper wall of the slot 11. The operator then continues to turn the spindle to the left, by which, owing to its screw threaded engagement with the threads 3, the spindle will be caused to travel in an upward direction and draw upon the collar 13, by which an upward pull upon the head 9 will be exerted. In this operation, it will, of course, be understood that the head 9 remains stationary against rotation relative to the spindle, and in its upward travel effects the gradual extraction of the cork 15 without any twisting strain thereon.

20 The operation of the device will, it is thought, be fully understood from the foregoing description, and it will be seen that a cork extracting device of simple construction is provided by which a cork may be quickly and conveniently extracted from a bottle. It will also be seen that, in the operation of extracting the cork, the portion 2 by fitting over the upper end of the neck of the bottle will reinforce the same, thus preventing any liability of breakage of the bottle during the extraction of the cork. The screw construction of the extracting means permits of the removal of the most refractory corks without the necessity of the operator exerting great force. As the casing 1 may tend to turn slightly on the neck during the operation of extracting the cork, it will be understood that it may be held sufficiently to overcome this objection by one of the hands of the op-

erator, while the other hand of the operator 40 is employed to manipulate the handle 5^a.

Having thus described the invention, what is claimed as new, is:—

A cork extracting device comprising a frame or casing having a threaded opening at 45 the upper end thereof, a cork-screw provided at its upper end with a head, said head being formed at its upper end with clutch teeth and at its lower end with a transverse slot, and having a bearing opening communicating at 50 its lower end with the slot, the upper wall of which forms a bearing shoulder, a screw spindle engaging the threaded opening in the casing, and provided with a smooth surfaced lower end journaled in said bearing opening 55 and extending into the slot, a clutch member on the screw adapted to engage the clutch member on the head, whereby the screw may be coupled to the head to rotate the screw in one direction for projection into the cork, 60 and a contact member on the lower end of the spindle vertically movable and revoluble in the slot in the head and adapted to contact with said bearing shoulder, whereby the spindle may be rotated reversely to draw the 65 clutch member thereof out of engagement with the clutch member on the head and to bring said contact member into engagement with the shoulder, by which on the continuous reverse revolution of the spindle the cork-screw may be withdrawn without rotation. 70

In testimony whereof, I affix my signature in presence of two witnesses.

WILLIAM J. STANTON.
